DEVICE FOR THE TREATMENT OF ARTIFICIAL SILK

Application filed January 2, 1931, Serial No. 506,182, and in Germany January 24, 1930.

This invention relates to a process for the manufacture of artificial silk and to a device for carrying out the said process. The invention more particularly refers to the liquid treatment of threads spun on bobbins which by the methods at present in use, when washed or otherwise treated in liquids, have to be taken from the bobbin holders of the spinning machines and placed one by one into the washing devices, where the bobbins have to be properly tightened up. It is obvious that this type of operation wastes considerable time and is besides, detrimental to the wet threads under treatment.

15 The invention avoids these drawbacks in that it enables the washing or other liquid treatment to be carried out so that the bobbins may be taken directly from the spinning machine into the washing device in large numbers and washed without any appreciable intermediate handling.

In order to carry out this new method, the invention provides a frame which is constructed so as to itself form a portion of the washing or other liquid treating device. The bobbins are taken from the spinning machine and placed directly into the said frame, whereupon the frame, after being 20 closed, is transferred to the washing machine as a whole.

These and other objects and improvements of the invention will best be understood by reference to the accompanying drawings, 25 which illustrate the novel frame for the liquid treatment of the threads and the washing device, by way of example.

Fig. 1 is a part sectional front elevation of the new frame with a number of bobbins 30 fixed in position for washing.

Fig. 2 is a cross section thereof on line II—II of Fig. 1, while Fig. 3 is a plan view of that figure with parts shown in section.

45 Fig. 4 illustrates the liquid treating device with a number of frames arranged in position for washing the cops thereon, the figure being a part-sectional front elevation,

Fig. 5 is a side elevation thereof,

50 Fig. 6 shows a plan view, and

Fig. 7 a similar plan view of the liquid distributing box.

Referring particularly to Figs. 1 to 3, *c* denotes the frame proper, which may be made of wood or metal, and which is provided with three fixed sides, while the fourth side *d* is movable. Bars *e* of preferably cross-shaped or star-shaped section are arranged between the loose member *d* and the opposite side member of the frame, and are adapted to receive the filled bobbins *a*, which are separated from one another and also held fast by means of soft rubber washers *f*. The movable side *d* of the frame is guided at both ends on pins *g* carried in suitably arranged lugs or bearings on the frame, and is provided with holes or depressions *b* for the reception of the cross-like sectioned bars *e* and with India rubber packing rings *i*. The fast member *c'* at the other end of the frame is provided with drilled holes *k* in which the reduced ends of the bars *e* are received and through which the liquid is allowed to enter the bobbins. India rubber packing rings *i* are likewise provided as in the aforedescribed loose member *d*.

The bars *e* with the bobbins *a* and India rubber rings *f* thereupon are inserted in the frames at the spinning machines by first moving the loose side down to as far as the bearings *g'*. Then the bars *e* are introduced with their reduced ends into the depressions *b* of the movable side so as to lean with their upper ends against the last *l* of the upper fixed member *c'*, whereupon the movable side *d* is lifted until the bobbins on the bars *e* are tightly closed between the packing rings *i* of the upper and lower members. The upper reduced ends of the bars thereby enter the holes *k* of the upper fixed member *c'*, and at the same time the bobbins *a* and India rubber washers *f* are pressed firmly together. Both, the bars and the bobbins thereon are now firmly held in position and may be locked by means of wedge pieces *h*. In this condition the whole frame can be removed to the liquid treating device.

The washing or other liquid treating device is illustrated in Figs. 4 to 7. It consists

in its essential parts of the distributing box *m* for the liquid, having suitably attached pipe sockets *n* positioned at the same distances from each other as the holes in the washing frame. The said frames are placed onto these sockets and pressed down tightly by means of a knuckle lever *o* or the like.

The device according to the invention is preferably used not only for the washing of the threads but also for other wet treatments, especially for desulphurizing. In such cases the frames may remain in the washing device in which only the liquid is changed, or they may be removed and transferred to another device of a similar kind. After treatment the bobbins are dried in the same frames on which they had passed through their wet treatment.

As will be gathered from the foregoing description, the essential feature of the new process according to the invention consists in that the bobbins are placed in the washing frames directly at the spinning machines in which they pass through the whole further process until the silk is completely dried and finished. Thus, from the spinning machines to the end of the process no more handling of single bobbins is necessary, but only of complete frames containing a large number of bobbins, whereby a time-saving and very convenient way of handling is provided. The best results of this new process can be observed with silk of the more sensitive kinds of which the output and quality have been considerably improved.

The dried silk is preferably wound straightaway onto suitable bobbins or but it may, of course, also be reeled into the form of hanks as desired.

What we claim is:

1. In a device for treating artificial silk, a washing device comprising a distributing box for the liquid, a frame comprising a loose and a fixed side member situated opposite to each other, bars between said side members for

the reception of the bobbins and of interposed packing rings, means to lock said loose members in a raised position, holes formed in said fixed side members for the reception of said bars, the treating liquid passing through said holes on its way to the bobbins, and pipe sockets on the distributing box in contact with said holes.

2. In a device for treating artificial silk, a portable frame for carrying silk bobbins, comprising in combination, a carrying member, a loose member situated opposite the first-mentioned member, means for connecting said members, a plurality of bars adapted to receive said silk bobbins and carried by said members, packing rings on said bars, holes formed in the first-mentioned member and adapted to receive an end of each of said bars, a space being left between the walls of said holes and said bars for the passage of the treating liquid, cavities formed in the second-mentioned member and adapted to receive the other end of each of said bars, pins connected with said means and guiding the second-mentioned member, and means for locking the second-mentioned member.

3. In a device for treating artificial silk, a washing device comprising a distributing box for the liquid, a frame comprising a loose and a fixed side member situated opposite each other, means for moving said loose member, means for maintaining said loose member in position, depressions formed in the loose member, holes formed in the fixed member, bars of cross-shaped section placed between said loose and fixed member, the ends of said bars being reduced for insertion in said depressions and holes, and pipe sockets on said distributing box in contact with said holes.

In testimony whereof we affix our signatures.

FRITZ PASCHKE.
PETER FRANZEN.
